DESIGN FOR A TRAY

Simon W. Farber, Brooklyn, N. Y.

Application June 14, 1938, Serial No. 77,820

Term of patent 14 years

To all whom it may concern:

Be it known that I, Simon W. Farber, a citizen of the United States, residing at Brooklyn, in the county of Kings and State of New York, have invented a new, original, and ornamental Design for a Tray, of which the following is a specification, reference being had to the accompanying drawing, forming part thereof.

Figure 1 is a top plan view, Figure 2 is a side view, and Figure 3 is an end view of a tray, showing my new design.

I claim:

The ornamental design for a tray, substantially as shown.

SIMON W. FARBER.
